(57) **CLAIM**

The ornamental design for a pin cover for an inversion table, as shown and described.

DESCRIPTION

FIG. 1 is a bottom rear perspective view for a pin cover for an inversion table showing my new design;

FIG. 2 is a top view thereof;

FIG. 3 is a front view thereof;

FIG. 4 is a left-side view thereof;

FIG. 5 is a right-side view thereof;

FIG. 6 is a front view thereof;

FIG. 7 is a rear view thereof;

FIG. 8 is a sectional view taken along lines 8-8 from FIG. 6 thereof;

FIG. 9 is a sectional view taken along lines 9-9 from FIG. 6 thereof;

FIG. 10 is a bottom perspective view, thereof; and,

FIG. 11 is a top, right-side perspective view shown in an environment of use.

The broken line showing of an inversion table depicts environment and forms no part of the claim.

1 Claim, 8 Drawing Sheets
